PERPETUAL CALENDAR

Louis Berkower, Bronx, N. Y.

Application July 26, 1947, Serial No. 763,885

3 Claims. (Cl. 40—109)

1

This invention relates to calendars, and more particularly to perpetual calendars, and still more particularly to calendars which may be made of sheet material.

The object of my invention is to provide a calendar which may be made of relatively inexpensive sheet material, such as sheet Celluloid or glazed sheet metal or cardboard wherein there is provided a mounting sheet and a slide, which members, in relation to each other, may outline through a window all possible combinations of indicia outlining the month, to provide a perpetual calendar.

In the more specific phase of my invention, it is contemplated by me to provide a perpetual calendar having a mounting sheet which outlines a window or mask, the size corresponding to an outline of seven columns and six rows whereby the window may mask a slide carrying indicia arranged uniformly in the form of thirteen columns and six rows, whereby a relative slidable movement of the slide to the mask will make visible through the window seven columns and six rows selected from the thirteen columns and six rows of figures, whereby any predetermined month of the year correlating the days thereof coincident with the actual day and week may be obtained during any month or year.

Still more particularly, it is an object of my invention to provide a perpetual calendar which may be made of simple stampings and efficiently and inexpensively serve the intended purpose.

To attain these objects and such further objects as may appear herein or be hereinafter pointed out, I make reference to the accompanying drawing forming a part hereof, in which:

Figure 1 is an exploded perspective view of one embodiment of my invention;

Figure 2 is a fragmentary assembled view in one position thereof;

Figure 3 is a fragmentary perspective view in another position;

Figure 4 is a partial perspective view of another embodiment of my invention;

Figure 5 is a fragmentary sectional view taken on the line 5—5 of Figure 2.

Making reference to the drawing, it is contemplated by me to provide a perpetual calendar in which a slide 10 includes a composite calendar 11 comprising indicia outlining the days of the month by employing columns 12 which are thirteen in number, and rows 13 which are six in number, with the seventh row 14 including provision for designating intelligence hereinafter more specifically described.

2

The arrangement of a composite monthly calendar is predicated upon the possibility that with the masking out of all but seven of the columns, all of the days of the month may be portrayed and by merely correlating the numerals with some fixed relationship corresponding to the days of the week, any possible arrangement of the calendar may be secured.

In accordance with the more specific embodiment of my invention, I outline a slide 10 in the form of a quadrant whose upper edge 15 and lower edge 16 are concentric, with a common center. The sides edges 17 and 18, respectively, extend to each edge of the vertical columns 12, as will appear more clearly hereinafter.

With a slide of the character described, I provide a cover or mounting member 19. I form a mask therefrom by the vertical slits 20 and 21, so that the edges 22 and 23 outline the side edges 20 and the ends 24 provide the upper and lower extremities. The spacial position of the sides 22 and 23 corresponds to the special position of seven columns 12 on the slide 10. The slits so formed provide a medially positioned web 25 for purposes which will appear hereinafter. In the construction provided I outline a zone 26 which is divided into seven segments 27, each having indicia outlining the days of the week, beginning with Sunday and ending with Saturday.

With the construction thus described, I may thread the slide 11 into the slits 22 and 23 to guide the upper edge 15 adjacent the upper ends 24 and 24 of the slits and to guide the lower edge adjacent the lower ends 24 and 24. Under these conditions, the mounting 19 serves as a guide to hold the slide 10 by the distortion with respect to each other of the web 25 and the main body of the mounting 19, as will more clearly appear from an inspection of Figure 5. Sliding action of the slide with respect to the window defined by the edges 22, 23 will permit the date indicia to be in the form of columns and rows to be visible within limits corresponding to seven days of the week.

In the embodiment illustrated I have made the mounting sheet 19 of general angular outline so that the edges 28 and 29 conform to the edges 17 and 18 in angular position. The displacement between the edges 28 and 29 plus the overhang 50 beyond the columns previously described is such that in either extreme position of the slide, the edges 17 and 28, and 18 and 29 may be made co-terminous and thereby act as limiting guides for sliding movement to either extreme position.

As an additional feature, I include a disk 30,

which is divided into twelve segments 31, each having indicia corresponding to the months of the year, with further indicia 32 to outline the number of days in the month as they may vary from twenty-eight to thirty-one. A bearing hole 33 is provided for alignment with the bearing aperture 34 on the mounting sheet, a cutout 35 being provided to mask the segments 31 upon alignment of the bearing hole 33 and bearing aperture 34. A trunnion in the form of a bolt 36 whose shank is screw-threaded, aligns the disk 30 through the bearing hole 33 and bearing 34. A knurled head 37 and nut 38 are provided to frictionally tension the disk in any angular position.

In the embodiment illustrated, I have located the bearing 34 within the limits of the slits 20, 21 between the ends 24 and 24 thereof. In such construction I prefer to provide a guide slot 39 in the slide 10, the slide concentric with the edges 15 and 16 and whose extreme ends 40, 40 extend for a distance corresponding to six columnar spaces. The location of the guide slot 39 is complementary to the bearing 34 and the radial position of the hub 33 from the cutout 35.

Upon assembly of the slide 10 with the backing sheet 19, the fastening bolt is first passed through the slot 39 and then through the bearing hole 34 and the bearing hole 33, before attaching the nut 38. In this way it will be observed that the common fastening element serves the multiple purpose of a trunnion for the disk 30 and a limiting guide for the slide 10 which, upon tensioning of the knurled head 37, fixedly holds the disk, slide and mounting sheet 19 with relation to each other after an adjustment has been made.

In the embodiment illustrated in Figures 1 to 3, a perpetual calendar disclosing a single month has been exemplified. I may, however, combine a group of such slide assemblies and mountings as more clearly illustrated in Figure 4, whereby three consecutive months may be assembled on a single mounting backing.

In the illustration, the backing sheet 41 of rectangular outline is chosen and is provided with slits 42, 43, leaving a web 44 and a masking area defined by the edges 45, 46. Masking apertures of similar construction 47 and 48 are provided. Each of the masking areas 46, 47 and 48 is provided with slides 49, 50 and 51, respectively, guided within slits of the same construction as in the prior embodiment, with the modification to take care of the rectangular outline of the slits in parallelism with each other instead of radially positioned as in the embodiment illustrated in Figures 1, 2 and 3. Each of the slides 49, 50 and 51 is provided with guide slots 52 which cooperate with the fastening element 53 to frictionally hold the slide in any adjusted position.

The slide 49 may have associated with it the disk 54 adjacent the cutout 55, to have the common fastening element 53 pivotally mount the disk 54 while limiting the sliding movement of the slide 49 to the limits of the guide slot 52. The slides 50 and 51 may have associated therewith month indicating disks 56 and 57, respectively, by fastening elements 58 and 59 adjacent cutouts 60 and 61 to view the months indicated on the disks 56, 57. Cutouts 62, 63 provide clearance for the fingers to manipulate the disks to a new radial position, while permitting the bottom edge 64 to rest on a flat surface, should the calendar be employed as a supporting base in show card fashion.

It will thus be observed that I have provided a perpetual calendar which is simple in construc-

tion, inexpensive to manufacture, and by the expedients described I obtain a slide which rigidly holds the sliding members for the monthly adjustment which is necessary to place the calendar into use. Thus, by the employment of Celluloid or like sheeting, cardboard, metal and paper composites, or etched thin sheet metal, I take advantage of the resiliency of the sheet material to secure a frictional engagement for the slide and mount.

10 The relative adjustment of the slides to the respective windows need not be more fully described to secure a perpetual calendar adjustment as this will be clearly apparent.

Having thus described my invention and illustrated its use, what I claim as new and desire to secure by Letters Patent, is:

1. A perpetual calendar comprising, in combination, a slide of rigid sheet material having outlined thereon columns and rows of indicia to outline the days of the month, to outline thirteen columns and six rows, a cover member of sheet material cut away to form a window uncovering seven columns transversely revealing all the rows, said window being outlined by a pair of slits in parallelism to the columns, extending substantially the height of the slide to provide front and rear guides for the slide, the ends of the slits forming edge guides for the slide along the rows of indicia of the slide, the movement of the slide for six columnar positions along the rows revealing a month of figures through said window, a pivot member on said rear guide, a disk having radially outlined indicia for the various months of the year revolvably mounted on said pivot, said cover having a cutout to unmask said disk at a portion thereof, said pivot member passing through said disk and slide, stop portions for said slide comprising a guide slot thereon, the ends whereof form stops for said pivot, said guide slot having its ends spaced apart for a distance of six columnar positions on said slide.

2. A perpetual calendar comprising, in combination, a slide of rigid sheet material having outlined thereon columns and rows of indicia to outline the days of the month, to outline thirteen columns and six rows, a cover member of sheet material cut away to form a window uncovering seven columns transversely revealing all the rows, the window being outlined by a pair of slits in parallelism to the columns, extending substantially the height of the slide to provide front and rear guides for the slide, the ends of the slits forming edge guides for the slide along the rows of indicia of the slide, the movement of the slide for six columnar positions along the rows revealing a month of figures through said window, a pivot member on said rear guide, a disk having radially outlined indicia for the various months of the year trunnioned on said rear guide, said pivot extending from said slide and serving as a cover member to said disk and slide, a guide slot on said slide having its end portion spaced apart for a distance of six columnar positions of said slide and screw threaded means for said pivot to lock said disk and slide in predetermined position.

3. A perpetual calendar comprising, in combination, a slide of rigid sheet material having outlined thereon columns and rows of indicia to outline the days of the month, to outline thirteen columns and six rows, a cover member of sheet material cut away to form a window uncovering seven columns transversely revealing all the rows, the window being outlined by a pair

of slits in parallelism to the columns, extending substantially the height of the slide to provide front and rear guides for the slide, the ends of the slits forming edge guides for the slide along the rows of indicia of the slide, the movement of the slide for six columnar positions along the rows revealing a month of figures through said window, a pivot member extending normally through the rear guide and centrally of the window defined by the slits, a disk trunnioned on said pivot having radially outlined indicia for the various months of the year revolvably mounted thereon and positioned with respect to the cover member to extend adjacent the perimeter of the slide, a cutout portion on the cover member to mask all but a month outlining indicia on said disk, said slide having a slot spanning said pivot extending the length of six columns of said slide, to restrict the exposure of said slide through said window to seven columns of indicia thereon. 20
